UNITED STATES PATENT OFFICE.

DANIEL DARROW, OF NEW YORK, N. Y.

BARGE-CONVEYER.

1,265,624.

Specification of Letters Patent.

Patented May 7, 1918.

Application filed January 29, 1917. Serial No. 145,137.

To all whom it may concern:

Be it known that I, DANIEL DARROW, a citizen of the United States of America, and residing in the city, county, and State of New York, have invented a certain new and Improved Barge-Conveyer, of which the following is a specification.

My invention relates to barges, particularly brick barges, and the object of my invention is to provide a conveyer to facilitate and expedite the loading and unloading operations on brick barges.

Referring to the accompanying drawings, Figure 1 is a broken transverse section 10 through a brick barge and conveyer;

Fig. 2 is a broken plan of portion of the barge and conveyer; and

Fig. 3 is a side elevation of the barge partially broken away and showing the conveyer in end elevation.

The brick barges in general use comprise flat bottom scows having a flat deck on which the load of bricks is carried. In loading such a barge, the customary practice heretofore followed has been to form piles of brick starting at opposite ends of the barge and approaching the middle of the latter from each end simultaneously or alternately at opposite ends so as to maintain the barge in trim. When the barge is fully loaded a mid passageway between the two piles is left open to permit the unloading operation to proceed in the reverse direction, viz., by removing portions of the piles at each end simultaneously, or first one and then the other, so as to prevent the barge becoming overweighted at either end.

To load a barge has necessitated heretofore a crew of men comprising a group on board the barge, another group on the loading pier, and frequently a third group which receives the bricks from one group and passes them on to the other. When the loading pier is considerably above the barge deck, as occurs at low tide, it not infrequently happens that a fourth group of intermediate handlers is necessary to form a complete loading or unloading crew. The bricks are ordinarily passed several at a time in what is called a "hand of brick" comprising six or seven bricks arranged side by side and handled as a unit. The loading and unloading operation by hand in this fashion is slow and expensive and is attended by considerable incidental loss, since trucks waiting to be loaded from the barge lose

from twenty-five to thirty minutes during the loading operation. Since several loads are carried during the day, it is obvious that as much as a couple of hours may be lost by a single truck standing idle during the successive loading operations thereof.

To overcome these losses I have provided a traveling conveyer mounted transversely on the barge and movable from one end to the other of the latter for handling the bricks expeditiously on both loading and unloading operations.

In the accompanying drawings the barge 10 is of the usual flat bottom construction 70 having a deck 11, with marginal stringers 12, within which the deck load of brick is carried. Just inside the longitudinal stringers, on opposite sides of the barge, I have provided guide channels 13 and 14 in which 75 run the supporting wheels 15 and 16 at opposite ends of the frame 17 of a traveling conveyer. Intermediate legs 18 and 19 with rollers 20 and 21 bearing freely upon the deck of the barge may be provided to support the weight of the frame. A mast 22 is provided at one end of the conveyer frame and is supported by lateral struts 23 and 24 and longitudinal struts 25.

The conveyer proper comprises a pair of 85 endless chains 26 and 27 between which extend contiguous supporting slats 28 provided at intervals with cleats 29 spaced apart a slightly greater distance than that occupied by a hand of brick 30. These chains 90 pass around sprocket wheels 31 and 32 on a shaft 33, driven by an explosion engine 34 carried at one end of the conveyer frame 17. At the opposite end of the conveyer the chains pass around a drum 35 at the free 95 end of a boom 36 pivoted at 37 to the longitudinal beams of the frame 17. The boom 36 may be raised or lowered by cables 38 passing from their point of attachment 39 over pulleys 40 at the head of the mast 22 100 and thence to winding drums 41 operated through gears 42 and 43 and hand crank 44. If desired, a counter mechanism 450 may be mounted on the boom 36 in such position that it is actuated by successive hands of 105 brick thus affording a record of the number of brick piled on or discharged from the barge.

The motor 34 is mounted at one end of the frame and preferably aligned with the latter so as to take up as little room as possible lengthwise of the barge thus economizing

space and permitting the usual load to be taken by the barge. The motor is preferably an explosion engine driving a fly-wheel 45 on the main driving shaft 46. A worm 47 on this shaft meshes with a worm wheel 48 on the transverse shaft carrying the sprocket 49 through which and the chain 50 motion is transmitted to the conveyer sprocket 33. A change speed and reverse mechanism is arranged on the shaft 46 at the gear box 51, as also a clutch at 52, operated by the hand lever 53.

In order to move the conveyer as a whole lengthwise of the barge, I provide a pair of chains 54 and 55 which may lie in the channels 13 and 14 adjacent the longitudinal string pieces, but are sufficiently loose to be carried up over guides 56 and 57 to sprocket wheels 58 arranged on jack shafts 59-60 geared at 61 and 62 to the shaft 63. A clutch 64 operated by lever 65 connects this shaft to the main driving shaft 46.

When the conveyer is to be shifted lengthwise of the barge the clutch 64 is thrown in, thus driving the jack shafts 59 and 60 and through them the sprockets 58 which engage the chains 54-55. Inasmuch as the latter are held stationary by their end fastenings, 66, the conveyer is shifted on the barge in a direction depending on the direction of rotation of the sprockets 58, which in turn is controlled from the gear box 51 on the main driving shaft.

Various modifications of details of construction and arrangement of parts will readily occur to those skilled in the art without departing from what I claim as my invention. Thus the method of shifting the conveyer frame lengthwise of the barge may be variously modified and in fact can be altogether dispensed with since the workmen loading the bricks on the conveyer could, without difficulty, push the frame to proper position. It is to be understood of course that the conveyer does not possess great weight since its width is slight, needing only sufficient space to accommodate a single hand of brick, or at most two hands of brick side by side on the supporting slats 28. A conveyer twenty inches in width is amply sufficient to accommodate a double hand of ordinary brick and still leave a margin for clearance.

The operation of the apparatus is readily understood. In loading a barge the conveyer would be moved to one end of the barge and the boom 36 adjusted to proper height for the convenience of the workmen on the loading pier or dock. The conveyer being set in motion, the loaders on the dock 60 would place hands of brick on the conveyer as it passes around the upper end of the arm 36 and a second set of loaders would be stationed on the barge to remove the brick from the conveyer and pile them on the barge. When a suitable number of bricks have been piled at one end of the barge the conveyer would be shifted to the other end of the barge and this operation repeated until a complete load of bricks 70 has been symmetrically piled on opposite ends of the barge. The conveyer travels with the barge to the point of unloading and the unloading operation is merely a reversal of the loading, except that it is possible to 75 so arrange the upper end of the boom 36 that it discharges directly into a cart without handling the bricks at this point. The truck loading operation is thus a very rapid one, since the full shift of men may be so employed in loading the conveyer and the speed of the latter may be accelerated as may be necessary to accommodate it to the workers on the barge.

I claim as my invention:

The combination with a deck loading barge, of a loading and unloading apparatus therefor comprising a frame extending transversely of the barge but movable lengthwise above the deck thereof, a vertically adjustable boom at one end of the frame adapted to be swung outboard of the barge, a conveyer belt carried by said frame and boom and having a horizontal reach extending across the major portion of the barge deck at convenient height for manual loading thereon and unloading therefrom, together with means for driving said conveyer belt.

In testimony whereof I have signed my name to this specification, in the presence of two subscribing witnesses.

DANIEL DARROW.
